PICNIC OUTFIT

Henry Rothschild, New York, N. Y.

Application August 18, 1941, Serial No. 407,370

2 Claims. (Cl. 311—99)

This invention relates to new and useful improvements in picnic outfits, and relates more particularly to a novel, self-contained unit which, when closed, resembles a conventional suitcase or traveling bag in external appearance, and which, when opened, provides a completely equipped picnic table with hinged legs, space being provided within the case for all of the essential articles needed for usual picnic requirements.

One of the principal objects of the present invention is to provide a novel container having foldable legs of improved construction, and which, when the case is open, may be quickly moved into operative position, the exterior of the case serving as the table top.

A further object of the invention is the provision of a novel drawer structure contained in one of the hinged sections comprising the case, the other section having a novel arrangement for the reception of the other essential articles for a picnic outfit, including foldable chairs.

Still another object of the invention is the provision of an improved hinged leg assembly for picnic tables, card tables, and the like, wherein the several pivoted leg structures are capable of being quickly moved into operative position, and when the case or table is not in use, the leg assembly is readily moved into folded position entirely within the confines of the case or table.

A further object of the invention is the provision of a novel locking arrangement for foldable legs employed in connection with tables and the like.

In the drawings:

Fig. 1 is a perspective view of the preferred embodiment of the present invention, the case being fully opened and being in usable position.

Fig. 2 is a perspective view of the case when in closed position.

Fig. 3 is a bottom plan view of the structure shown in Fig. 1 with the hinged legs in folded position.

Fig. 4 is a section taken on line 4—4 of Fig. 3, the legs, however, being shown in open position.

Fig. 5 is similar to Fig. 4, but shows the legs in partly folded position.

Fig. 6 is a broken section showing the details of the locking arrangement for the foldable leg assembly.

Fig. 7 shows the relation of the parts when the spring lock has been depressed.

The case in closed position is shown in Fig. 2 and is designated by the reference character 10. The case is generally rectangular in shape, and includes a pair of complementary sections 11 and

12 which are of substantially the same size and shape, and which are pivotally joined together by means of hinges 13 (Fig. 2). The internal arrangement of section 11 is shown in Figs. 1 and 3 wherein one of the end walls or gussets 15 is provided with a substantially rectangular opening 16 through which a drawer 17 passes. The cross-sectional dimensions of the drawer are slightly less than the size of opening 16 in order to permit free inward and outward movement of the drawer, and the outer end wall or face 18 of the drawer is of such size as to fit relatively snugly within opening 16 when the case is closed, as shown in Fig. 2. The top 19 of the drawer is adjacent to the outer surface of section 11, which serves as half the table top when the case is open, the outer surface of section 12 serving as the other half of the table top, all as shown in Fig. 1. If desired, these outer side walls may be covered with decorative fabric, as shown at 20.

Drawer 17 is supported for sliding movement by means of transverse supports 21 secured at their opposite ends to the end walls 15 of section 11. The lower surface of drawer 17 is further provided with a drawer pull 24 and a spring locking element 25, all as shown in Fig. 3. Dishes and flatware are desirably carried in drawer 17, and conventional straps or other securing means may be employed for preventing movement of these articles while the case is being carried.

Sections 11 and 12 are each provided with a pair of leg structures 27 and 28 which are pivoted adjacent to walls 29, which walls 29 are the upper walls of the case when the same is closed, a handle structure 33 being secured to wall 29 on section 11. Each leg is supported in a substantially U shaped bracket 30 secured to end walls 15, a pivot pin 31 passing through the opposed walls of the bracket and the leg. Bracket 30 is secured below edge 32, as shown in Fig. 4, in order that when the legs are in closed position they will lie entirely within the confines of the case. The legs are rigidly maintained in open position by means of a lever 35 which is centrally pivoted at 36 in walls 29. A link 38 is pivotally connected at one end thereof by means of a pivot pin 39 with leg 27, and at its opposite end an angular extension 41 is connected with one end of lever 35 by means of a pivot pin 42. A link 45 is pivotally connected with leg 28 by means of a pivot pin 46, and at its opposite end an angular extension 47 is secured adjacent the opposite end of lever 35 by means of a pin 48.

The following means are provided for locking the legs in open position. One end 49 of lever

35 is formed with a cut-out portion forming an edge 50 serving as a locking bolt. When the legs are in fully open position, edge 50 lies substantially in alignment with pivot pins 42 and 48, and when in this position such edge is engaged by a projection 52 on a spring catch 53 secured at its inner end to wall 28 by means of rivets 54. A headed plunger 55 is positioned within an aperture 56 in wall 28, the head engaging the inner surface of spring catch 53, as shown in Fig. 6. When it is desired to release lever 35, the plunger 55 is moved inwardly, as shown in Fig. 7, thus causing a projection 52 to leave edge 50 and permit the legs to be folded.

In order to give the several legs additional stability when in open position, a second link 57 is pivotally secured at one end thereof, as at 58, to the leg at a point slightly below pivots 39 and 46, and at its opposite end link 57 is secured at 60 to an angle bracket 61 which is slightly spaced from each U shaped support 30. In section 12 a generally rectangular metal box 64 may be positioned, such section also being adapted to receive two or more folding chairs 65, and a thermos bottle 66 may be positioned at each end of box 64, thus completing the picnic equipment assembly. When the case is in closed position, as shown in Fig. 2, the upper meeting edges thereof are secured by means of conventional locking elements 67. The number of chairs which section 12 may carry may be in-

creased by making this section somewhat deeper than section 11.

What I claim is:

1. In a picnic outfit having a pair of complementary hinged sections which when closed form a carrying case, and when opened form a table top, the combination of a leg structure at each corner area of the case, said leg structure being foldable transversely completely into the open case, and means for rigidly securing the legs in open table supporting relation, said means comprising a lever which is centrally pivoted on the inner surface of each end wall of the open case, a link connecting each end of the lever with a leg at a point spaced from the pivotal mounting of such leg, and means releasably securing such lever against movement.
2. In a table structure having a pair of complementary hinged sections which when closed form a carrying case, and when opened form a table top, the combination of a leg structure at each corner of the open table foldable transversely completely into the open case, and means for rigidly securing the legs in open table supporting position comprising a substantially centrally pivoted hinged lever, links connecting opposite ends of the lever with the legs, and stop means for securing the lever in open position.

HENRY ROTHSCHILD.
